(57) **CLAIM**

The ornamental design for training robot cell, as shown and described.

DESCRIPTION

FIG. 1.1 is a perspective view of a training robot cell;

FIG. 1.2 is a top view of FIG. 1.1;

FIG. 1.3 is a front view of FIG. 1.1;

FIG. 1.4 is a back view of FIG. 1.1;

FIG. 1.5 is a left side view of FIG. 1.1;

FIG. 1.6 is a bottom view FIG. 1.1; and

FIG. 1.7 is a right side view FIG. 1.1.

In the drawings, the ornamental design that is claimed is shown in solid lines. The broken lines form no part of the claimed design.
